HEEL LIFT ATTACHING MACHINE

William J. Young, Peabody, Mass., assignor to
 W. J. Young Machinery Company, Lynn,
 Mass., a corporation of Massachusetts

Application July 30, 1938, Serial No. 222,175

18 Claims. (Cl. 1—32)

This invention relates to means for attaching top lifts to heel bodies, and particularly for attaching leather lifts or tread layers to wood heels. However, the materials of which the heel bodies and top lifts or tread pieces are made, are not factors or limitations of the invention.

The objects are to provide an effective and satisfactory means for centering the lift and heel body, to combine such centering means with automatic nail driving means, and to provide improvements in nail feeding, positioning and driving means by which enhanced speed, accuracy and efficiency are obtained, and to afford means for quick and easy adjustments and substitutions of parts to be made whereby to accommodate heels of different styles and dimensions and to effect the union between the heels and top lifts by different numbers and patterns of nails.

The invention consists in machines having means for accomplishing the foregoing objects, and other characteristics set forth in the following specification, not only in the specific form there described, but in all equivalent mechanical embodiments of like means and combinations.

In the drawings furnished to illustrate the invention—

Fig. 1 is a front elevation of a machine embodying the invention;

Fig. 2 is a right hand side elevation of the machine;

Fig. 3 is a side view, partly in section, of a wood heel with an attached leather top lift showing the result accomplished by the operation of the machine;

Fig. 4 is a vertical section of the upper part of the machine taken on line 4—4 of Fig. 1;

Fig. 5 is a detail section taken on line 5—5 of Fig. 4;

Fig. 6 is a detail section taken on line 6—6 of Fig. 5 and represented on a larger scale;

Fig. 7 is a cross section on line 7—7 of Fig. 6;

Fig. 8 is a horizontal section on line 8—8 of Fig. 1 and a plan of the parts below said line;

Fig. 9 is a vertical section on line 9—9 of Fig. 8;

Fig. 10 is a partial section similar to Fig. 9 showing one of the movable parts of the machine in a different position;

Fig. 11 is a detail section on line 11—11 of Fig. 9;

Figs. 12 and 13 are perspective views showing the gauges by which the heel body and lift are centered or aligned with one another preparatory to the nailing operation;

Fig. 14 is a sectional view of the nail magazine

and a part of the feeding means by which nails are conducted from the magazine to the driving position. This figure is a section taken on line 14—14 of Fig. 1;

Fig. 15 is a sectional elevation of the hopper and nail guiding means taken on line 15—15 of Fig. 14;

Fig. 16 is a detail section of a portion of the nail feeding means taken on line 16—16 of Fig. 14.

Like reference characters designate the same parts wherever they occur in all the figures.

The effect produced by the machine is shown in Fig. 3, where *a* represents a wood heel body, *b* represents a leather top lift or tread piece, and *c* represents nails which are driven through the top lift into the heel body for securing the one to the other. The nails here shown are unlike conventional nails, brads or tacks, in that they have neither heads nor points, but are similar to 20 dowels in that respect. They may be made by simply cutting off suitable lengths of wire of suitable gauge, without further operations. Being headless they are driven at different inclinations with respect to one another in order to 25 hold the attached lift securely by the divergence of those portions which pass through the lift. Although differing from ordinary nails in the respects noted, they are otherwise analogous and will be referred to as nails in this specification, 30 and it will be understood that the driving means of the machine is adapted to drive headed nails as well.

The operating parts of the machine are mounted in a frame 1 which, in the design here 35 illustrated, is secured to a base 2 which is adapted to rest on the floor and has a bracket 3 attached to one side of it supporting a driving motor 4. Such frame and motor may, however, be otherwise supported within the scope of the invention. 40

Secured to the front of the frame are parallel brackets 5, 5 supporting between them a block 6 which is both a support for heels to be operated on, a receiver for nails to be driven, and a guide for a number of nail drivers. Said brackets and 45 blocks have complementary parallel ways 7 constructed suitably to permit removal of the block and substitution of other blocks in which the nail driver guideways are provided in different numbers and patterns. The block is secured 50 immovably in place by clamping means of any suitable character known to mechanics, not shown, or necessary to be shown, here. The top surface 8 of the block is the part which supports the heel to be operated on, as shown in Fig. 4. 55

The lift *b* in the present illustration is of larger dimensions than the tread end of the heel body and must be properly centered with respect thereto so that a sufficient margin will be left for trimming to the prescribed final contours and outline. This is the usual condition with respect to leather top lifts applied to wood heels. For this purpose a breast gauge *9* and two pairs of side gauges or clamps *10, 10* and *11, 11* are provided. The breast gauge is secured to the block *6* and is formed with a face adjacent to the supporting surface *8* against which the breast of the lift *b* abuts, and an overhanging lip *12* for engagement with the breast of the heel body. It is secured adjustably to the block *6* by screws *13* passing through slots *14*, (see Fig. 13). With other types of heel, however, the top lift may be smaller than the heel body, and for such cases the breast gauge may be reversed and placed with the lip *12* next to the supporting surface. Or gauges with similar lips of different widths, or with no lip at all, may be substituted for one another.

The side gauges *10, 10* and *11, 11* are mounted in parallel planes on pivot studs *15, 15*, rising from a carrier *16* which is approximately in the same plane with the supporting surface *8*. The gauges *10* overlap this surface and are adapted to engage the sides of the lift *b*, being of less thickness than the lift and located so near the supporting surface that they may pass beneath the edges of a heel body wider than the top lift; while the gauges *11* are supported by spacers *17* in a higher plane, clear of the lift and are adapted to engage the sides of the heel body. The members of each pair of side gauges have intermeshing gear teeth *18* which cause them to turn equally and oppositely when either of such members is moved around its pivot stud, and they are drawn together by springs *19* arranged substantially as shown in Fig. 8. Adjustable stop screws *20* and *21* coact with an abutment *22* on the carrier *16* to position the side gauges for lifts and heels of different widths, so that the flaring inner faces at the extremities of such gauges will be held apart widely enough to admit the breast end of the lift and heel body, and points on such faces within the extremities will bear on their sides. One stop screw is threaded through a lug on the upper side of one of the lower side gauges, and the other screw is similarly mounted in a lug on the under side of the relatively opposite member of the top pair of gauges, so that both screws are enabled to bear on the same abutment. The range of independent adjustment of the two pairs of gauges enables heel bodies which are wider than their top lifts, as well as those which are narrower, to be properly centered, and also accommodates a wide range of heels.

The guides for nail drivers and pockets to receive nails to be driven are provided by sleeves *23* set into passageways formed through the block *6* with a close driving fit and are thus securely held frictionally. The bores in the upper parts of the sleeves are large enough only to receive and guide the nails and the drivers *24*, which are of approximately the same diameter as the nails. The lower ends of the sleeves are enlarged to fit slidably the larger and more rugged parts *24a* of the drivers which protrude from the sleeves and are engaged by the impeller or pusher later described. These guides and drivers are thus made of different diameters in their different portions to prevent bending and buckling of the small nails while being forced

into obdurate material such as seasoned hard-wood, and to provide essential stiffness in the protruding thrust-receiving parts of the drivers.

The nail driver impeller is a bar *25* which reciprocates in a vertical guideway *26*, secured to the frame *1* beneath the drivers, and has at its upper end a platform *25a* of sufficiently large dimensions and suitably located to engage and apply pressure to the lower extremities of the drivers. Preferably, although not necessarily, the impeller carries a plate *27* on which the ends of the drivers bear. As the drivers, many of them, are inclined to the vertical, that is, to the direction in which the impeller is moved, their ends are displaced laterally in being advanced. Hardened screws or plugs *27a* (Fig. 9) are set into the plate under the drivers and have smooth end faces on which the abutting ends of the drivers bear. Their function is to prevent formation of grooves in the plate due to sliding contact of the drivers, and to make adjustments in compensation for whatever wear occurs. Springs *28* surrounding the drivers and confined between the block *6* and abutment disks *29* secured to the drivers hold the latter retracted whenever permitted by the impeller. Downward movement of the latter is limited by the guide *26* against which a shoulder *25b* on the impeller bears when in the lowermost position.

A lever *30* is connected at one end by a pivot *31* to the lower end of the impeller *25* and is connected at its opposite end by a pivot *32* with a link or connecting rod *33* which is coupled by a pivot *34* with an operating lever *35*, here shown as having a treadle so that it may be depressed by the foot and weight of an operator. This treadle lever is pivoted at *36* to a bracket *37* on the foot of the base, and is normally elevated by a spring *38* anchored to a pin *39* on the side of the base.

The lever *30* is connected at an intermediate point in its length by means of a pivot *40* with a rod *41* rising to a pivot connection at *42* with a lever *43* which is pivoted at *44* to a bracket *45* on the upper end of the frame *1*. The opposite end of lever *43* is slotted lengthwise to receive a pivot *46* which connects it with a two part adjustable rod *47a, 47b*, which slides in aligned guideways *48, 49* on the frame and carries a clamp *50* on its lower end. Said clamp is adapted to bear on the seating face, or upper end, of a heel body resting on the work support (block *6*) and clamp the heel body thereon, at the same time resisting and counteracting the thrust applied by the drivers in setting the nails. It is pivoted to the rod at *51* so as to be self adjusting to different heels of which the seating faces extend at different inclinations.

Adjustment of the clamp to heels of different heights is effected by changing the over all length of the two part clamp rod. For this purpose one of the parts as *47b* has a threaded extension *47c* which is screwed into a threaded socket *47d* in the other part or member. A lock nut *52* is threaded on the extension *47c* to secure the adjustments effected by turning one member relatively to the other.

The springs *28* and *38* normally hold the drivers retracted and the treadle and heel clamp raised, in the positions shown in the drawings. When the treadle is depressed, the lever *30* first turns about its pivot connection *31* as a fulcrum, lowering, or permitting to be lowered, the linkage carrying the clamp *50*, until the latter is stopped by the heel. Thereafter continued de-

pression of the treadle turns lever 30 about the pivot 40 as a fulcrum, and raises the impeller 25, causing the nail drivers to be advanced and the nails driven into the heel. Owing to the manner in which the lever 30 is coupled to both the impeller and the heel clamp, the same continuing motion of the lever advances both, successively in relatively opposite directions, and the force application of the lever causes the pressure exerted on the heel by the clamp to be proportional to the effort required to drive the nails.

After each nailing operation, the gauges are withdrawn, the heel last operated on is removed, the drivers are retracted, and the nail receiving spaces or chambers in the supporting block are again charged with nails by means which I will now describe.

A nail magazine or hopper 53 of cup-like form rotates about a horizontal axis on a stud shaft 54 secured to an upright 55 (Fig. 2) on a platform 56 having a bracket 57 secured to the side of the frame. A stationary cover plate 58 is mounted on the platform across the open end of the magazine and has an inlet 59 in its upper part. The walls of the rotating part of the magazine are provided with lifter vanes or buckets 60 arranged and formed to carry nails upward from the mass in the bottom and discharge them from points at and near the top side of the magazine. An inclined table 61 is supported from the stationary cover plate by arms 62 in the space surrounded by the lifters 60. It is inclined downward toward the cover wall steeply enough so that any nails which fall upon it will roll or slide off, no matter how they are positioned when striking the table. The upper surface of the table contains spaced parallel grooves 63 extending along the slope of the table to receive and guide those nails which happen to fall into them. A deflector 64 is secured to the cover wall 58 above and forward of the table at an opposite inclination thereto, so as to deflect and guide upon the table those nails which happen to drop from the lifters too far forward to be supported and guided by the table. Conductor tubes 65 are mounted in the lower part of the front wall 58, each in the same vertical plane, and in approximate alignment, with one of the guide grooves 63 of the table. These tubes extend through the front wall and are aligned with extension tubes 66. Terminal tubes 67 are mounted in a forward extension of the hopper supporting platform 56, being secured detachably therein by set screws 68. A nail feeder or escape device 69 is mounted across the outlet ends of all the terminal tubes 67. It is a cylindrical bar mounted rotatably with its axis horizontal and transverse to the terminal tubes, so as to block the outlets therefrom, and it has transverse passages 70 adapted to be brought, by partial rotation of the feeder, into alignment with the terminal tubes.

The tubes 65, 66 and 67 of each group are in alignment with one another, or nearly enough in alignment, and mounted at a sufficiently steep inclination, to conduct nails by gravity from the receiving table 61 to the feeder 69. More than enough nails to keep the tube groups full at all times fall into the locating grooves 63 of the receiving table and enter the several receiving tubes. There are as many aligning grooves and tube groups as the largest number of nails ever required to be used for the purposes of the machine. In order to adapt the machine to use less than this maximum number, one or more

of the intermediate tubes or tube sections 66 is removed and for it there is substituted a solid bar or equivalent obstructor. It is for this reason that the intermediate section is made separate from the terminal sections 65 and 67; and the supporting structure is so made that it is readily removable and replaceable. A shallow socket is provided for the lower end of the section 66, in alignment with the terminal section 67, as shown in Fig. 14, and notches 71 are formed in the stationary hopper wall 58 to receive the upper end and locate it in alignment with the receiving tube 65. But it is to be understood that a single continuous tube may be used instead of any one or more of the sectional tube groups for conducting one or more nails.

Conductor tubes 72 lead to a transferer or loader 73 (Figs. 9 and 10), which transfers nails to the supporting block 6, as will be presently described. The upper ends of these conductor tubes are fixed in a row parallel to the feeder cylinder, each in the same vertical plane with one of the tube sections 67, but at an angle to such section. The vertex of this angle is in the axis of the feeder 69, hence by partial rotation of the feeder its passageways 70 may be brought into alignment with the tubes 67 and 72 alternately to receive nails from the former and discharge them into the latter. Lugs 74 and 75 on the feeder coact with a fixed stop 76 to limit the angular movements of the feeder to the positions in which the above described alignments occur. A fixed shield 77 adjacent to the feeder prevents the nails from passing out of the passageways 70 when the latter are in alignment with the tubes 67 and until they come into register with the tubes 72.

The conductor tubes are flexible so that their lower ends may be shifted to deliver nails in accordance with different prescribed patterns or arrangements of nails in the heel. In a heel with a wide tread area the nails are set farther from the center than in a heel with a smaller tread area, and may be more numerous. Different blocks 6 are substituted for one another according to the number and spacing of the nails required for different heels, and the transferer 73 used in any case has nail receiving channels 78 in the same number and spacing as those in the supporting block. Different transferers are interchangeable with one another, as will be presently described. Consequently the lower ends of the conductor tubes are shiftable to accommodate such different patterns. Their lower ends are received and frictionally held in socket tubes 79 which are secured to, and rise from, a pattern plate 80 above the loader 73.

The magazine is mounted at a sufficient height to permit gravity feed of nails to the pattern plate, and to enable the lower ends of the conductor tubes to be more or less displaced without obstructing such feed. And the hopper is continuously rotated at a speed which insures fall of correctly located nails on the table 61 in excess of the needs of the machine and maintains at all times a reserve supply of nails in the aligned tubes 65, 66, 67. The motor 4 thus rotates the hopper by means of a belt 81, pulley 82, pinion 83 on the shaft of pulley 82, an intermeshing gear 84 on a parallel shaft 85 (Fig. 6), a pulley 86 on the shaft 85, and a belt 87 surrounding the latter pulley and the hopper.

The nail loader or transferer 73 previously mentioned is secured detachably by bolts 88 (Figs. 75

8 and 9) on a slide or carriage 90 which reciprocates in a horizontal guideway 91 attached to one side of the main supporting frame. The traverse of the loader is from the position shown in Figs. 8 and 9, directly beneath the pattern plate 80, to the position shown in Fig. 10 directly over the supporting block 6. In one position the passages 78 of the transferer are in register with corresponding passages 92 of the pattern plate, and in the other its passages register with corresponding driver guideways 23 in the supporting block. A bottom plate 93, which also has holes 94 in the same pattern as the passages 78, is provided to obstruct these latter passages when receiving nails from the pattern plate. The bottom plate is slidable in a dovetail guideway in the loader (see Fig. 11), and has a lug 95, against which a spring projected plunger 96 of the carriage 90 acts to hold the bottom plate normally with its openings 94 out of register with the passages 78. This lug is arranged to abut against a shoulder 97 on the supporting block as the loader advances, when the holes 94 are aligned with the driver guides. A shoulder 98 is suitably located on the carriage to strike the lug 95 and arrest the carriage when the passages 78 of the loader thereafter register with the holes 94; and an adjustable stop screw 99 is mounted in a cross bar 99a on the outer end of the carriage guideway to arrest the carriage when, in its outward movement, the passages 78 register with those in the pattern plate.

The pattern plate 80 is detachably mounted in a frame 100 on top of the guideway 91 and is secured by a set screw 101, whereby different pattern plates may be readily substituted for one another.

Automatic mechanisms, controlled by the treadle, operate the nail feeder and loader, and displace the heel side gauges from the path of the loader. These mechanisms comprise the following parts.

A shaft 102 (Fig. 6) aligned with shaft 85 and independently rotatable, carries a drum 103 and a crank disk 104 which are made fast to the shaft by set screws, (as are also the gear 84 and pulley 86 made fast to the shaft 85). These aligned shafts rotate in bearings on standards 105 and 106 supported by a bracket 107 on the side of the frame 1 (Figs. 1 and 2). The drum 103 is surrounded by a brake band 108, the ends of which are penetrated by a rod 109 (Fig. 7) and are drawn together by a spring 110 acting against one of such ends and reacting against an adjustable abutment nut 111 screwed upon one end of the rod. A pin 112 projecting from one side of the gear 84 engages the opposite end of rod 109 and through the latter applies torque to the brake band. The band exerts friction sufficient to rotate the drum 103 when the latter is unobstructed, but is enabled to slip when the drum is positively prevented from rotating. The drum is thus prevented by a latch 113 (Figs. 1 and 5) which is normally held by a spring 114 in the path of a projection 115 on the circumference of disk 104. A crank pin 116 on said disk is coupled by a link 117 with an arm 118 on a rock shaft 119 to which a second arm 120 is secured. Arm 120 is pivoted to a block 121 (Fig. 9) slidably mounted on a connecting rod 122 which is attached by a pivot pin 123 to the slide or carriage 90. Springs 124 and 125 surrounding the connecting rod at opposite sides of the block 121, and confined between abutments 126 and 127 on the rod, trans-

mit the movements of arm 120 in opposite directions to carriage 90 and yield to permit stoppage of the carriage at points short of the full throw of the arm. When the crank disk makes a complete rotation counter-clockwise with respect to Figs. 1 and 5, it swings the arm 120 first to the left and then to the right. In its leftward travel the arm moves more than far enough to bring loader 73 into delivering register with the supporting block 6. When the loader reaches the position of register, it is arrested by the coming together of the lug 95 and shoulders 97 and 98; and spring 124 thereafter yields to permit further movement of arm 120. The yieldable connection between the carriage and its driver permits a long enough pause before reversal of the carriage to ensure that the nails will drop out of the loader; and enables the stopping location of the carriage to be accurately established by the lug and shoulders, avoiding necessity of constructing the power linkage with such extreme accuracy as would otherwise be necessary to ensure exact register of the small passages in the loader with those in the driver block.

The rock shaft 119 carries also a cam 128 (Figs. 1 and 5) which cooperates with an arm 129 on a rock shaft 130 transverse to 129, extending into the interior of the frame 1 and carrying an upright 131 on its inner end; (see also Fig. 4). A spring 132 connects arm 131 with an anchorage on a fixed part of the frame, normally holding this arm in the position shown and causing the arm 129 to bear on the upper side of cam 128. Arm 131 is connected by a pin and slot connection 133 with the carriage 16 (30) on which the heel gauges 10 and 11 are mounted. The cam 128, turning counter-clockwise from the position shown in Fig. 5 while arm 120 swings to the left, raises arm 129 and, through the connections with the gauge carrier 16 above described withdraws the gauges from the path of the loader. It also holds them out of the way while the loader is advanced over the block 6 and retracted clear of the block.

Carriage 90 controls or operates the feeder 45. One of the trunnions or pivots of the feeder carries on its outer end an arm 134 (Figs. 2 and 16) connected by a helical tension spring 135 with an arm 136 (Figs. 1 and 8) on a rock shaft 137 which turns in a bearing 138 on the guide 50 91 and extends over the carriage 90. An arm 139 is secured to shaft 137 in the path of a block 140 on the carriage, and these parts are so located that when the carriage is retracted in the position which registers the loader with the pattern plate, the feeder is held in the position shown in Fig. 14, where its passageways 70 register with the conductor tubes 72. A spring 141 (Fig. 16) is coiled around the pivot extension of the feeder and reacts between a pin on the stationary frame and the arm respectively in a manner to turn the feeder into register with the tube sections 67, when arm 139 is unrestrained. Spring 135 is much stronger than spring 141, whereby it overcomes the resistance of the latter when pulled upon by the arm 136 under the action of the loader carriage, and yields only when the stop lug 74 is arrested by the pin 76. It is encased and protected by a shield 142 secured to the side of guideway 91.

The operating lever 35 controls the nail feeding mechanism by means of a lever 143 (Fig. 4) pivoted at 144 to a bracket on the frame and having on the end of one arm a pin 145 which overlies that arm of the main lever 30 which is con- 75

nected to the link 33. The other arm lever 143 is connected by a pin and slot connection 146 with an upright bar or rod 147 fitted slidingly in a stationary guideway 148 and connected to a 5 spring 149 which is anchored by means of a pin 150 to the frame. This spring tends constantly to raise the rod 147 and holds the pin 145, or an antifriction roll mounted on said pin, in contact with the lever 130. Hence, whenever the treadle 10 is depressed, the rod 147 is raised; and it is lowered when the treadle is raised. Spring 38 which raises the treadle is enough stronger than spring 149 to overcome the latter without yielding to any considerable or objectionable extent.

15 The rod 147 carries a pawl 151 normally held by a spring 152 against a stop pin 153 so that its extremity or toe underlies the extremity of a horizontally extending arm 154 which is a part of, or connected with, the latch 113. Conveniently the 20 latch and arm are made as two arms of a bell crank lever pivoted on a stud 155. Pawl 151 yields when, in rising, it encounters arm 154; but depresses this arm when descending, and so withdraws the latch from arresting position with respect to the projection 115 of the crank disk. 25 The pawl quickly passes and releases arm 154 in its descent, whereupon spring 114 restores the latch to its normal position in the path of the projection on the crank disk, ready to arrest the 30 latter on completion of one rotation.

In the normal position, the position of rest, of the machine, the parts thereof occupy the locations shown in all of the figures of the drawings except Fig. 10. In order to attach a tread piece *b* to a 35 heel body *a*, the operator places the tread piece on the support 6 against the breast gauge 9 and between the side gauges 10, 10, places a heel body on top of the tread piece against the breast gauge and between the side gauges 11, 11, and depresses 40 the treadle 35 with force enough to drive a number of nails simultaneously into the heel. The first part of the movement brings the clamp 50 down on the heel body, and the balance of the treadle movement in the same direction drives the 45 nails.

Upon release of the treadle, the bar 147 descends and trips the latch 113. Thereupon the motor driven mechanism advances the loader 73 carrying a charge of nails over the supporting 50 block, withdraws the side clamps from the path of the loader, and then returns the loader and side clamps to their previous positions. At the same time it permits the feeder 69 to be turned by its spring 141 into position to receive nails from 55 the delivery tubes. The loader pauses over the supporting block shortly before, while and shortly after the crank pin 116 passes the dead point, which affords ample time for the charge of nails to be deposited in the block. It then returns to starting position and as it reaches that position turns the feeder 69 so that a new charge of 60 nails is delivered to the loader. The crank disk is then arrested and the mechanisms driven by it remain at rest until another heel is nailed.

65 It will be apparent that the machine is substantially automatic, requiring care and effort on the part of the operator only to place the thread lifts and heel bodies between the gauges and to step on the treadle. The leverage of the treadle 70 is so great and the driving distance so short that moderate force application suffices to drive the nails into heels made of the hardest woods. The gauges correctly centralize the heel body with respect to the tread piece and avoid danger of 75 any accidental misalignment. These gauges are

quickly adjustable for both tread pieces and heel bodies of different dimensions independently of one another. The machine is adjustable readily for placing nails in different numbers and arrangements in heels of different dimensions. 5 The novel application of springs facilitates such adjustments and avoids danger of breakage of any of the operating parts in case of mistake or oversight in making any such adjustment, besides enabling accuracy to be obtained in the registration of narrow passageways, with the greatest of ease.

What I claim and desire to secure by Letters Patent is:

1. In a machine of the character described, a 15 heel support having nail and nail driver guiding passageways, nail drivers movable in said passageways, an impeller for the drivers, a clamp mounted in opposition to the heel support, an operating lever, connections between said lever 20 and impeller, and other connections between said lever and clamp, each of said connections being arranged as a fulcrum for the other, whereby the force exertion of the lever simultaneously applies holding force by the clamp and driving force to 25 the drivers with each force in opposition to the other.

2. A nailing machine comprising a support having a guideway for a nail and a nail driver, an impeller movable to cause propulsion of nails from 30 said guideway, a work clamp movable toward and away from the work support in approximate alinement with the nail guideway, a lever having a pivotal connection with said impeller, a link having a pivotal connection with said lever at a 35 distance from the first named pivotal connection, and coupling means between said link and clamp, the lever having a force applying arm extending laterally from one of said pivotal connections at the opposite side thereof from the other pivotal 40 connection.

3. A nailing machine having a work support, a clamp movable toward and away from said work support for holding work pieces thereon, a nail driver operable in said work support for forcing 45 a nail into an article clamped on said support, and a single operating lever in force applying and fulcrum relation to both said clamp and driver for causing work clamping and nail driving actions in relatively opposite directions by movement of the lever in one direction.

4. A nailing machine comprising a work support, a clamp movable toward and away from said support for holding work pieces thereon, an impeller movable in substantial alinement with 55 said clamp in a location and manner to cause driving of a nail from said support into a work piece thereon, an operating lever having separated fulcrum connections with both said clamp and said impeller and having an operating arm 60 at one side of said fulcrum connections, one of said connections including means for causing movement of the clamp oppositely to movement of the impeller when the lever is operatively moved in one direction.

65 5. A nailing machine comprising a work support having driver guideways, nail drivers movable in said guideways and protruding below said support, an impeller movable in the general direction of the driver movement for actuating the 70 drivers to set nails in objects mounted on the work support, a clamp carrier movable toward and away from the work support above the position of the work pieces thereon, a clamp connected to said work carrier, a lever pivoted above 75

- the work support connected to the carrier, a lever connected to the impeller, and a link pivotally connected with both levers, the second named lever having an operating arm so arranged that 5 its movement in one direction causes the clamp carrier to be moved toward the work support and the impeller to be moved in the opposite direction, whereby the work clamping and nail driving means react against one another.
10. 6. In a machine for attaching tread lifts to heel bodies, a work support, a pair of tread lift gauges overlying said work support adapted to engage the sides of a tread lift placed thereon, a pair of side gauges for heel bodies mounted above 15 the tread lift gauges at a height therefrom sufficient to clear the tread lift, the gauges of each pair being pivotally mounted, spring impelled toward one another, and geared together for movement in unison in relatively opposite directions.
20. 7. In a machine for attaching tread lifts to heel bodies, a work support, a pair of tread lift gauges overlying said work support adapted to engage the sides of a tread lift placed thereon, a pair of side gauges for heel bodies mounted above 25 the tread lift gauges at a height therefrom sufficient to clear the tread lift, the gauges of each pair being pivotally mounted, spring impelled toward one another, and geared together for movement in unison in relatively opposite directions.
30. 8. In a machine for attaching tread lifts to heel bodies, a work support, a pair of tread lift gauges overlying said work support adapted to engage the sides of a tread lift placed thereon, a pair of side gauges for heel bodies mounted above 35 the tread lift gauges at a height therefrom sufficient to clear the tread lift, the gauges of each pair being pivotally mounted, spring impelled toward one another, and geared together for movement in unison in relatively opposite directions.
40. 9. A nailing machine comprising a work support having channels for receiving nails, driving means for ejecting nails from said channels, a loader movable back and forth between a receiving position and a loading position over the work 45 support, a nail hopper, means for conducting nails from the hopper to the receiving position of the loader, an escape device interposed in said conducting means, means for moving the loader back and forth, means for actuating the escape device to feed nails when the loader is in receiving position, and means controlled by the nail driving action for causing the loader to advance into loading position and return to receiving position when the nail driving means are retracted 50 after setting nails.
55. 10. A nail driving machine comprising a work support having nail receiving channels, drivers for displacing nails therefrom into work pieces on the work support, a back and forth moving actuator for the nail drivers, nail feeding and loading means operable to carry nails to the work support and charge the nail receptacles therein, normally inactive operating mechanism for causing the nail feeding and loading means to perform their functions, and means controlled by the driver actuator for setting the operating means into action on the return travel of said actuator.
60. 11. A machine for attaching tread lifts to heel bodies comprising a support having a surface 55 against which a tread lift and superposed heel body may rest and nail receiving and driver guiding passages opening through such surface, a loader movable over and aside from said work support having nail carrying passages arranged to be brought in register with said nail guiding passages when the loader is placed over the support, gauges disposed over said support for centering heel bodies and lifts with respect to said guiding passages, and means for moving said gauges out of the way of said loader when the loader is brought over the support.
65. 12. In a machine of the character set forth, the combination with a work support having a supporting surface and passages opening through 15 said surface for reception of nails and for guidance of nail drivers, of gauges disposed adjacent to said supporting surface for centering a heel body and tread lift relatively to said passages, and means for moving said gauges away from 20 said supporting surface to permit placement of nails in said passages.
70. 13. The combination in a machine of the character described, of a support having nail guiding passages opening through its supporting surface, heel centering gauges mounted adjacent to said support in position for locating a heel in a predetermined relation to said passages, said gauges being movable aside from the support, a loader also movable across and aside from the 25 support having means for carrying nails to the said passages, and correlated operating mechanism constructed and operating to move said gauges and loader each out of the way of the other when either is brought across the support.
75. 14. In a machine of the character described, a supporting member having a supporting surface and nail guiding passages opening through such surface, a gauge carrier, gauges supported by said carrier over said supporting surface arranged 30 to center heels in a given relationship to said passages, the gauge carrier being movable in a path which displaces the gauges from their heel engaging position, and a loader guided to move over and away from the support in a path intersecting the path of the gauges and having means for carrying nails to said nail passages.
80. 15. The machine combination set forth in claim 13 and comprising further correlated mechanism for moving said gauges and nail loader so that 35 the gauges are displaced clear of the loader when the loader advances to nail delivering position with respect to the work support, and vice versa.
85. 16. In a machine of the character set forth, a work support having a nail guiding passage 40 opening through the supporting surface thereof, a driver guided to move through said passage, a clamp movable toward and away from the support in a path and location enabling it to clamp work pieces on the support, a common operating lever for said driver and clamp having pivots at 45 separated points connected for applying force to said driver and clamp respectively, and power applying means engaged with said lever at a third point at one side of the before named pivots.
90. 17. A nailing machine comprising a work support, a clamp movable toward and away from said support for holding work pieces thereon, a nail driver movable in substantial alignment with 50 said clamp at the opposite side of the work supporting location from the clamp, two levers, one of which has a pivotal pressure applying engagement with the clamp and the other a similar engagement with the nail driver, a fixed fulcrum 55

for one of said levers, a power applying means pivoted to the other of said levers, and a link connected to both levers.

17. In a nailing machine, the combination of 5 a work support having a nail guiding passage, a nail loader having a passage through which nails can pass, movable from a receiving position at one side of the work support to a delivering position wherein its passage is registered with the 10 passage in the work support, positive stops for arresting said loader in each position, and means for moving the loader back and forth comprising a link connected to the loader, an arm movable back and forth in the general direction of movement of the loader, having a sliding engagement 15 with said link, and springs in reacting engage-

ment with the link on opposite sides of the arm; said springs being adapted to transmit movement of the arm to the loader and to yield when the loader is arrested by said stops.

18. In a nailing machine, a nail loader movable between a position in which it receives nails and a position for delivering nails, positive means for arresting the nail loader in each of said positions, a back and forth movable driving element for the nail loader, and means for transmitting 10 movement from said element to the loader comprising springs at opposite sides of said element in thrust transmitting connection with the loader.
